UNITED STATES PATENT OFFICE.

HENRY K. SANDELL, OF CHICAGO, ILLINOIS, ASSIGNEE TO MILLS NOVELTY COMPANY,
OF CHICAGO, ILLINOIS, A CORPORATION OF ILLINOIS.

ELECTRIC PIANO.

1,045,444.

Specification of Letters Patent. Patented Nov. 26, 1912.

Application filed July 5, 1910. Serial No. 570,432.

To all whom it may concern:

Be it known that I, HENRY K. SANDELL, a citizen of the United States, residing at Chicago, in the county of Cook and State 5 of Illinois, have invented a new and useful Improvement in Electric Pianos, of which the following is a specification.

My invention relates to improvements, more particularly, in the class of pianos 10 which are played by a traveling music-sheet, through the medium of which the hammers are actuated electrically or otherwise.

While the application of the more important features of improvement is not necessarily limited to electrical means for playing the instrument through the medium of the perforated variety of music-sheet, the invention was especially devised for that application, it being practically embodied in a 20 piano the hammers of which are actuated by electromagnets included in parallel circuits, or each in a branch-circuit of a generator contained in the common or main part of the circuit, adapted to be closed 25 through the perforations in a traveling music-sheet as they register, in the travel of the sheet, with circuit-closing contact mechanism between which the sheet passes.

The present invention relates primarily 30 to improved means, controlled by the traveling music-sheet, for modifying the tone of the instrument in accordance with the requirements of the music being performed by regulating the force of stroke of the 35 hammers; and other features of improvement will be hereinafter pointed out.

In the accompanying drawings, Figure 1 is a view in front elevation of a piano of the upright variety embodying my invention; Fig. 2, a view of the same in side elevation with a side of the casing broken away; Figs. 3 and 3^a present, respectively, in vertical sectional elevation, the improved means for regulating the force of stroke of 45 the hammers of the piano-action and, in front elevation, an electromagnet-device for operating said regulating means; Fig. 3^b is an enlarged section on line 3^b, Fig. 3; Fig. 4 shows, by an enlarged broken, sectional 50 view in side elevation, one of the electromagnet-devices illustrated in Fig. 3, with the pivotal armature and parts co-operating therewith in normal position; and Fig. 5, is a plan view of the same; Figs. 6 and 7 55 are, respectively, views in side and front ele-

vation of the electromagnet-device for controlling the string-dampers of the instrument, and Fig. 8 presents a diagram of the electric circuits for controlling the electromagnet-devices which operate the piano-action and the string-dampers and control the striking force of the hammers.

The "action" shown, and which is denoted A, as a whole, in Figs. 1 and 2, is one in common use in upright pianos, except 60 that for the sake of compactness, more particularly to adapt the instrument to be cooperatively combined, for duo or accompaniment playing, with an electric self-playing violin, it is divided into an upper 65 section A' and a lower section A² so arranged, relatively, as to cause alternate hammers of the two sections to register with successive strings, or sets of strings of the same pitch, of the instrument. Adjacent to 70 each hammer of the action are supported two electromagnet-coils 9 and 10, these coils forming, respectively, an outer row and an inner row for the hammers of each section of the action, the coils 9 being rendered of 75 relatively low resistance by winding their cores with heavy wire and the coils 10 being wound with lighter wire to increase their resistance, all for purposes hereinafter explained; and the two coils of different resistance for each hammer are connected in 80 multiple. The insulated wires for all of the hammer-actuating electromagnets are housed in metal boxes 11 and 12, of rectangular cross-section, supported above the 85 respective rows of magnets and provided with front walls 13 of insulating material carrying on their front faces rows of inclined metal strips 14 having binding-posts 90 on their lower ends for connecting the wires 95 of the electromagnets to the strips; to the opposite ends of the inclined strips the wires in the boxes are connected through front walls of the boxes as indicated in Fig. 3. The coils 9 and 10 of each pair 100 thereof are connected to a different strip 14.

A bar 15, for performing the stop-function hereinafter described, and which is provided with a soft-rubber sheath 16 to electrically insulate and cushion it, extends 105 lengthwise along each row of the electromagnets 9, 10, in advance of and above the row, the bar having arms 15' extending backwardly from its ends, by which arms the bar is pivotally supported on standards 110

17, to adapt it to be rocked. Behind their pivotal points two corresponding arms of the upper and lower stop-bars are connected by a link 19, and the lowermost of these connected arms is connected by a rod 20 with the stop-rod actuating device shown more clearly in Fig. 3^a, and constructed and operating as hereinafter described. Each coil 9 forms with the companion-coil immediately behind it a pair having a common armature 21, depressed between its ends, as shown at 22, to bring it closer to the magnet-poles and increase its attractiveness. The armature 21 is fulcrumed at 23 on the upright arm of an iron bracket 24 carrying the pair of magnet coils on an angle iron support 25, one of which supports is provided for each row of the pairs of coils. In the upper face of each armature 21 is inserted, near its free end, a platinum contact-plate 26. Each armature 21 is embraced between the arms of a rectangular iron yoke 27, pivotally and insulatedly supported at the bent rear ends of its arms, as represented at 28 (Fig. 4), on the upright arm of the bracket 24, which is embraced between the yoke-arms; and the forward, closed end of the yoke has attached to it, as by a pin 29, a rectangular metallic finger 30 extending backwardly over the top of the free-end portion of the armature and carrying a platinum contact-point 31 to engage the insert 26, and a similar finger 32 extended across the plane of a stop-rod 35 15. As will be observed, the armature and its yoke turn on different centers, at 23 and 28, respectively, to cause, when they are moved, the point 31 to rub against the surface of the plate 26 and insure good contact.

One terminal of the winding of each coil 9 is connected with the respective yoke at 33, its opposite terminal, as also a terminal of the winding of the coil 10, being connected with a strip 14, while the opposite terminal of the coil 10 is connected to the iron framework.

A stem 34 extends backwardly from the rear end of each armature 21, to which it is rigidly united to move therewith, the stem carrying on its rear threaded end an adjustable weight 35 to overbalance the armature and cause it to normally incline upwardly relative to the plane of the upper surface of the poles of the two magnet coils to which it belongs. These stems of the upper row of armatures carry buttons, 36 (see, particularly, Fig. 3^b), extending upwardly from them to engage, from underneath, by movement of the armatures under attraction, the usual wippens of the piano-action, thus, by such attraction of the armatures in the upper row thereof, to cause the hammers to strike the alternate strings of the instrument. From the lower armature-

70 stems 34 extend upwardly rods 37, passing loosely through an interposed perforated guide-board 38 and carrying on their upper ends buttons 36 to engage hammer-actuating levers of the piano-action for working the hammers which alternate with those moved by the upper row of armatures.

75 As will be understood from the foregoing description, each time a pair of the coils 9, 10, is energized, their armature is attracted and with it the respective yoke 27. In fact, the armature and yoke together compose an armature formed of two separable movable parts or sections. By the resultant movement of the section 21, its stem actuates the hammer controlled by it to strike a string. The force of the hammer-stroke is greatest when the respective stop-rod 15 is in its lowermost position and is slightest when the rod is in its highest position, both 80 of these positions being indicated by the dotted representations of the rod in Fig. 4, the full-line representation thereof being its intermediate normal position. The reason for this difference in the hammer-stroke is that when the stop-rod is in the lowest position it is not encountered by the finger 30 of the respective armature-yoke 27, until just before the complete downward movement of the armature, so that the greater 85 force of the coil 9 continues to advance the armature-section 21 throughout its movement and causes it to actuate the respective hammer forcibly to produce a loud tone by the hammer-stroke. With the stop-rod 100 raised above its lowermost position, however, the encounter therewith, in the downward movement of the yoke, of the finger 32 will arrest the yoke and cause the continued movement of the armature 21 to 105 separate the plate 26 from the contact-point 31, thereby cutting out the coil 9 and leaving the coil 10 in circuit to complete the attraction of the armature with weaker power and therefore causing it to actuate the hammer with weaker force, producing a softer tone, though without shortening the regular full stroke of the hammer. Obviously, 110 the higher the position of the rod 15 the sooner will it effect cutting out of the coil 9 and leave the high-resistance coil 10 to operate the hammer, and the softer, therefore, will be the tone produced by the hammer-stroke.

115 The advantage of the described arrangement involving the relatively low and high resistance coils 9 and 10 is threefold in playing the piano through the medium of a circuit-closing traveling music-sheet 39 (Figs. 1 and 2), which is fed by suitable 120 mechanism denoted C, as a whole, in the lower part of the piano-case and operated by an electric motor D to move between a metal contact-roller 40 and a series of metal contact-brushes 41 having wire-connections 125 130

with the coils 9, 10, as hereinafter described with particular reference to the diagram in Fig. 8. The threefold advantage referred to consists, first, in enabling control to be had of expression in playing the instrument; second, in economizing in current, since the high-resistance coils, which are used the most, use less current than the low-resistance ones; and, third, in preventing harmful 5 sparking at the brushes 41 in the frequent breaking of the circuit there which would be sufficiently violent, if the high-resistance coils were cut out at that point, to burn the music-sheet.

10 The matter of setting the stop-rods to different positions in playing the instrument is automatically effected by the perforated traveling music-sheet through the medium of the mechanism shown in Fig. 3^a, which is 20 supported in the bottom portion of the piano-case.

15 On an iron bed 42, rigidly supported in the piano-case and having a standard 43 rising from it, is fulcrumed midway between 25 its ends on the standard an armature-lever 44 normally held resiliently in horizontal position by an expansion-spring 45 connecting one end of the lever with the bed. With this same end of the lever 44 the rod 20 has 30 an adjustable and flexible connection, as shown at 46 in Fig. 3^a; and the opposite end of the lever carries a vertical rack 47 meshing with a pinion, indicated at 48, on a rotary shaft 49 journaled in a casing 50 sup- 35 ported on an elevated end-portion of the bed 42, the shaft also carrying a gear-wheel 51 which is geared to a fan 52 journaled on the casing and performing the function of a brake by operating against the resistance 40 of the air. The lever 44 extends over the poles of two similar electromagnet-spoils 53, 53, supported on the bed 42 to one side of the standard 43, and it also extends over the poles of two similar electromagnet-spoils 54, 45 54, supported on the bed 42 at the opposite side of the standard. The two electromagnet-spoils 53 are connected in series, as are also the two spools 54.

50 With the lever 44 in its normal horizontal position, the rod 20 holds the stop-rods 15 in their intermediate position, wherein they permit moderately loud playing of the instrument by causing the hammers to strike the strings with moderate force. When the 55 traveling music-sheet closes the circuit to energize the electromagnet 53, they attract the adjacent arm of the armature-lever 44, thereby raising its opposite arm and with it the rod 20 to depress the stop-rods 15, with 60 the result of augmenting the force of stroke of the hammers in action and thus increasing the loudness of playing; and when the traveling sheet causes the coils 54 to be energized, they attract the arm of the lever 65 44 adjacent to them, thereby causing the

rod 20 to raise the stop-rods 15 and moderate accordingly the striking-force of the hammers in action. The rack and pinion mechanism at one end of the armature-lever acts as a brake to prevent objectionable sudden movements thereof under the attractive force of the electromagnets.

70 A substitute for the "loud" pedal of the ordinary piano is provided for automatic operation in the form most clearly illustrated in Figs. 6 and 7, and also shown in Figs. 1 and 2: On a support 55, which may be a continuation of the bed 42, in the bottom part of the piano-case toward one side thereof, rise a pair of similar electromagnet-spoils 56, wound as described of the spools 9 to render them relatively low-resistant, and a single electromagnet-spool 57, wound like the spools 10 to render it relatively high-resistant, these spools 56 and 57 being 80 connected in multiple. Extending from the support 55 at right-angles to and below the spools 56 and 57 are two similar electromagnet-spoils 58, 58, connected in series and presenting their poles to a vertical armature 59 pivoted between its ends at 60 and held normally away from the poles by a spring interposed at 61, the upper end of the armature forming a catch 62 to releasably engage the free end of an armature 63 pivoted at its opposite end, as shown at 64, to extend over and be common to the poles of the spools 56, 57. A stop-arm 65 cooperates with a contact-finger 66 at its free end to cut out the spools 56, 57, as hereinafter described. A rod 67 extends upwardly from the armature 63 near its free end and connects it at 68 with the rocking bar carrying the series of string-dampers as usual in an upright piano.

100 By the construction just described it will be seen that the two magnets 56, together with the magnet 57, will start the movement of the armature 63, and as soon as it has been started the circuit through the magnets 56 is broken and consequently the armature moves the remainder of the distance only under the pull of the magnet 57. By using only the magnet 57 to continue the movement the pounding of the parts is 115 prevented. Since the circuit is only maintained through the magnet 57 for a sufficient length of time to complete the movement of the armature 63, it is necessary that the catch 62 operate to retain the armature in 120 its position against the magnets until it is desired to release the same.

125 The operation of this device is substantially the same as that of the expression-device hereinbefore described, for varying the force of the hammer-strokes; that is to say, when the circuit is closed through the traveling music-sheet by engagement with the roller 40 of a contact-brush 41 connected with the coils 56, 57, they attract the arma-

ture 63, thereby pulling the rod 67 to turn the damper-bar in the direction to withdraw the dampers from the strings. The resistance to be overcome in thus turning the 5 damper-bar requires the two coils 56 to be used, but the armature 63, in turning downwardly, separates from the contact-finger 66, the latter being stopped against movement under the attraction of its magnet by the 10 interposed stop 65, whereby these coils are cut out, leaving only the coils 57 of greater resistance in circuit, and the catch 62 is caused by its spring 61 to engage the armature 63 and hold it down until the catch 15 is released. This release is effected at the proper time by closing the circuit through the music-sheet to energize the coils 58, 58 to attract the catch-armature 59 and withdraw the catch from the armature 63, which 20 then rises to its normal position under the usual spring-tension of the dampers and restores the damper-bar to its normal position.

The further description of this invention 25 is with particular reference to the circuit-diagram of Fig. 8. The electric motor D is suitably geared to the music-sheet feed-device C, to drive the latter for effecting the travel of the sheet between the roller 40 and 30 contact-brushes 41 and 41^a. For starting and cutting out or stopping the motor by hand, a push-button 68 is manipulated to make contact at the points 69 and 70, thereby closing the motor-circuit which may be traced as 35 follows: From one side of a generator, indicated at E, over a wire w and branch w' through an electromagnet 74 provided with a pivotal armature 75; from the electromagnet 74 over wire w² through the push-button 68 and thence over wire w³ to the opposite side of the generator. By thus energizing the electromagnet 74 to attract the armature 75, the latter releases the pivotal spring-pressed armature 76 of an electro- 45 magnet 77, causing the last-named armature to contact at 78 with the wire w. Upon release of the button 68, when it separates from the contact-points 69, 70 and cuts out the electromagnet 74, the motor-circuit is 50 thus closed over the wire w and armature 76, thence over wire w⁴ connecting that armature with one side of the motor, to the opposite side of which the wire w³ is connected. To cut out the motor and stop the operation 55 of the machine, a push-button 71 is manipulated to make contact at the points 72 and 73, thus connecting wire w³ with a wire w⁵ leading to a contact-brush 41^a in line with the series of contact-brushes 41. The wire w⁵ 60 has a branch-connection w⁵⁵ with the electromagnet 77, from which a wire w⁷ connects with wire w⁴ at the armature 76. Thus, by pushing the button 71, the electromagnet 77 is energized to attract the armature 76 and break the contact at 78, where-

upon the armature 75 engages and locks the armature 76 in its attracted position.

Each of the hammer-actuating electro-magnet-devices, as also the expression-controlling device and the damper-controlling 70 device, is connected by a separate wire with a different contact-brush 41, as will appear on inspection of the circuit-diagram, so that the music-sheet, in traveling between the roller 40 and brushes 41, produces proper 75 contacts of the brushes with the roller to actuate the hammers for playing the music for which the sheet is cut, and to actuate the other said devices at proper times. When, at the end of playing a piece, the brush 41^a 80 contacts with the roller 40 through a perforation suitably provided in the music-sheet, the motor is automatically cut out, since thereby the electromagnet 77 is energized to attract the armature 76 and break the contact at 78.

The device indicated at F in Fig. 1 is a mere switch for turning, stopping and reversing the action of the music-sheet feed by which the sheet is wound from one roller 90 upon another, but neither it nor the feed form any part of the present invention, and need not, therefore, be herein described.

What I claim as new and desire to secure by Letters Patent is:

1. In combination with a piano-action, electrical hammer-actuating mechanism therefor comprising an electric circuit, an electromagnet therein having coils of different resistance, said coils being connected in parallel, an armature comprising sections movable relatively to one another, said sections jointly controlling the current through one of the coils, both sections being simultaneously movable when the magnet is energized, and a stop in the path of one of said sections to stop said section without stopping the other section, thereby interrupting the current through one of the coils. 95 100 105

2. In combination with a piano-action, 110 electrical hammer-actuating mechanism therefor comprising an electric circuit, an electromagnet therein having coils of different resistance, said coils being in parallel branches, an armature comprising sections movable relative to one another, said sections being electrically connected in said circuit in series with the coil in one branch, both sections being simultaneously movable when the magnet is energized, and a stop 115 120 in the path of one of said sections to stop said section without stopping the other section and open the circuit of the coil in said branch.

3. In combination with a piano-action, 125 electrical hammer-actuating mechanism therefor comprising an electric circuit, an electromagnet therein having coils of different resistance, said coils being in parallel branches, an armature for said magnet 130

- provided with an independently movable yoke and a hammer-actuating stem, said yoke and armature being electrically connected in said circuit in series with one coil in one branch and controlling the circuit through said coil, the armature and yoke being simultaneously movable when the magnet is energized, and a stop in the path of the yoke to stop the yoke without stopping the armature.
4. In combination with a piano-action, electrical hammer-actuating mechanism therefor comprising an electric circuit, an electromagnet therein having coils of different resistance, said coils being in parallel branches, an armature having a hammer-actuating stem, a yoke embracing the armature, said armature and yoke being independently movable on different centers, said armature and yoke being electrically in series with each other and with the coil in one branch, a separable contact between the free ends of the yoke and armature, both said armature and yoke being simultaneously movable when the magnet is energized, and a stop in the path of said yoke to stop said yoke without stopping the armature and thereby separate the contacts and de-energize the coil in series with the armature and yoke.
5. In combination with a piano-action, electrical hammer-actuating mechanism therefor comprising an electric circuit, an electromagnet therein having coils of different resistance, said coils being in parallel branches, a pivoted armature, a pivoted yoke embracing the armature, a hammer-actuating stem provided with an adjustable weight upon it carried by the armature, said armature and yoke being in said branch and connected in series with one another and the coil in said branch, both the armature and yoke being simultaneously movable when the magnet is energized, and a stop movable to different positions in the path of the yoke to stop the same without stopping the armature and thereby deenergize the coil in series with the armature and yoke, and electrically operated means for moving said stop.
6. In combination with a piano-action, electrical hammer-actuating mechanism having a moving part, a rocking stop-bar movable to different positions in the path of said moving part to vary the force of the hammer-stroke, an electrical device for moving the stop-bar, comprising an armature fulcrumed between its ends, a connection therefrom to the stop-bar, electromagnet coils on opposite sides of the fulcrum and having the armature in common, and means for energizing said coils for the purpose set forth.
7. In combination with a piano-action, electrical hammer-actuating mechanism hav-
- ing a moving part, a rocking stop-bar movable to different positions in the path of said moving part to vary the force of the hammer-stroke, and an electrical device for moving the stop-bar, comprising a spring-balanced armature fulcrumed between its end, a connection therefrom to the stop-bar, a brake device on the armature, electromagnets on opposite sides of the fulcrum and having the armature in common, and means for energizing said magnets for the purpose set forth.
8. In combination with a piano-action, electrical hammer-actuating mechanism having a moving part, a rocking stop-bar movable to different positions in the path of said moving part to vary the force of the hammer-stroke, and an electrical device for moving the stop-bar, comprising an armature fulcrumed between its ends and provided on one end with a rack-and-pinion brake-device, and electromagnets on opposite sides of the fulcrum, having the armature in common, a rod connecting the armature with the stop-bar, and means for energizing said magnets for the purpose set forth.
9. In combination with a piano-action, electrical hammer-actuating mechanism therefor, an electric circuit containing said mechanism, and an electric damper-operating device comprising an electric circuit, an electromagnet therein, having coils of different resistance connected in parallel, an armature common to said coils, a contact normally engaging said armature and mounted so that the engagement will be broken when the armature is attracted toward its magnet, said armature and contact being in circuit with one of the coils, and means connecting the armature with the damper.
10. In combination with a piano-action, electrical hammer-actuating mechanism therefor, an electric circuit containing said mechanism, and an electric damper-operating device comprising an electric circuit, an electromagnet therein having coils of different resistance, said coils being connected in parallel, a pivotal armature for said coils, a contact normally engaging the armature, said armature and contact being in the circuit of the coils and connected in series with one coil, a rod connecting the armature and the damper-bar, an electromagnet extending crosswise of said first-mentioned electromagnet, a pivoted armature for said last-mentioned electromagnet, a catch on said armature adapted to engage with the first mentioned armature, and a circuit for energizing said last mentioned electromagnet.
11. In combination with a piano action, electrical hammer-actuating mechanism therefor adapted to be actuated by a traveling music sheet, comprising an electric circuit, contact members in said circuit between which

- the music sheet travels, rows of pairs of electromagnet coils, the members of each pair being of relatively high and low resistance, one pair for each hammer of said action, and 5 each pair being connected with a different contact member, a hammer-actuating armature for each pair of said coils, a contact normally engaging each armature, each armature and contact being in circuit with one 10 of the coils of its pair a stop bar extending lengthwise of said rows and means for moving the stop bar to different positions in the paths of the armatures to separate the armature and its contact.
- 15 12. In a piano, the combination of a piano-action divided into a plurality of sections one above the other, electrical hammer-actuating mechanism therefor adapted to be actuated by a traveling music-sheet, comprising an electric circuit, contact-members 20 in said circuit between which the music-

sheet travels, a row for each section of pairs of electromagnet coils, the members of each pair being of relatively high and low resistance, one pair for each hammer of the action and each pair being connected with a different contact-member, a hammer-actuating armature for each of said pairs, a contact normally engaging each armature, each armature and contact being in circuit with one 25 of the coils of its pair, connected stop-bars extending lengthwise of said rows and movable to different positions in the paths of the armatures, and electric means operatively connected with said bars for moving them to different positions in the paths of the armatures to separate the armatures and contacts, for the purpose set forth.

HENRY K. SANDELL.
